UNITED STATES PATENT OFFICE.

LAWRENCE T. JOHNSON, OF CHICAGO, ILLINOIS.

GAME BOARD.

Application filed October 18, 1921. Serial No. 508,501.

To all whom it may concern:

Be it known that I, LAWRENCE T. JOHNSON, a citizen of the United States, and a resident of the city of Chicago, county of Cook, and State of Illinois, have invented certain new and useful Improvements in Game Boards, of which the following is a specification.

This invention relates to game boards, and more particularly to a representation of golf links, on which the playing of golf may be simulated in an interesting and instructive manner.

Other objects will appear hereinafter. The invention consists in the combinations and arrangements of parts hereinafter described and claimed.

The invention will be best understood by reference to the accompanying drawings forming a part of this specification, and in which,

Fig. 1 is a plan view of a comparatively long hole,

Fig. 2 is a plan view of a shorter hole, Fig. 3 is a view of a colored marker for determining the position of a ball, and

Fig. 4 is a view of a special die used in connection with the game to determine the advance of the markers.

The invention consists of a representation of golf links, having either nine or eighteen holes arranged in any suitable manner over the board, the fairway of each hole being provided with hazards of different kinds, such as bunkers, ponds, etc., the particular arrangement of the course being a matter of choice, examples of hazards being illustrated in the drawings. In the drawings only two holes, a long one and a shorter one, are illustrated, which embody all of the features of the game, the general hole structure being substantially duplicated in the other holes of the course, except for the length of the holes and number of playing positions disposed upon the fairway.

The hole, as represented in Fig. 1, is provided with a tee, a fairway and a green, such features being ordinarily provided in actual golf courses. Extending along the

fairway to the green are disposed rows of differently colored dots, the dots of each row being designated successively with the numerals 1 to 6 in Fig. 1, and by the numerals 1 to 4 in Fig. 2, the length of the hole, of course, determining the number of dots from the tee to the green, that is, the dots are spaced approximately even distances apart upon all the holes, so that a short hole will have a smaller number of positions than a longer hole. As shown in the drawings, some of the dots are placed to represent that a bunker or sand pit has been encountered, and in playing the game as here contemplated, a player encountering a bunker is penalized one stroke. A player landing in the pond, as shown in Fig. 2, adds one extra stroke and retires to the first position back.

Markers of any suitable type, as shown in Fig. 3, each corresponding in color to a row of dots, are provided for marking the advance of the ball toward the green. Each player selects a certain colored marker in playing the game, and such marker is moved on the dots corresponding in color therewith. Selection of the colored markers may be made by casting a die, the player throwing the highest number being entitled to the color he prefers. Any number of players up to four may participate in the game.

In order to determine the rate of advance of the markers on the dots, an indicator of any suitable kind may be used, but I preferably employ a specially prepared die, having one, two and three dots on three of its sides and similar dots on the other three sides, as shown in Fig. 4 of the drawings. When the die is rolled in the ordinary manner and shows one spot uppermost, for example, the player rolling the die moves his marker to dot number "1" of a color similar to his marker, each roll of the die counting one stroke. It will be seen that two rolls of the die will carry a marker on the green in exceptional cases, or to a point adjacent the green in ordinary cases, if one is fortunate enough to roll successive "threes" with the die and does not encoun-

ter a hazard; such advance corresponding to exceptional shots in the actual game of golf. On the other hand, if the player rolling the die is unfortunate in turning up 5 a succession of "ones" or "twos" his advance will be correspondingly slow with a much larger number of strokes. Upon shorter holes like that shown in Fig. 2 only one "three" is necessary to bring a marker 10 to a point adjacent the green.

Upon any marker reaching a position next to the green, or one position from the green, the marker is moved to the green and one stroke counted. On the green, each of 15 the players rolls the die once and counts each spot on the die as a stroke, this representing the total number of strokes necessary to "hole out." These strokes on the green are then added to the strokes taken 20 on the fairway to obtain the total number of strokes necessary for the particular hole played. If desired, a player, from positions adjacent the green and one position back from the green, may be required to roll 25 the die until he obtains the proper number to enable him to move to the green. For instance, if a player is two moves from the green, he must get a "two" to go onto the green, etc.

30 In playing the game the markers are placed on the tee of hole number 1. Each player then rolls the die in his turn and moves his marker the number of spots shown on the die. One stroke is counted 35 for each roll of the die while on the fairway. Upon reaching the position next to the green, the die is not rolled but a stroke is counted and the players move to the green. Players reaching positions more 40 than one move away from the green either move to the green or roll the die once and use only the number of moves necessary to reach the green. A player who has reached a position on the green in two shots of 45 course does not have to count an extra stroke. When all the players are on the green each player rolls the die once and counts each spot on the die as a stroke instead of counting each roll as a stroke, as 50 was done upon the fairway. A player landing in a bunker adds one extra stroke to his score and advances from the same position. A player landing in the pond adds an extra stroke and retires to the first position back. The player with the lowest 55 total score for the number of holes played, wins the game.

While I have illustrated and described the 60 preferred form of construction for carrying my invention into effect, this is capable of variation and modification without departing from the spirit of the invention. I, therefore, do not wish to be limited to the 65 precise details of the construction set forth, but desire to avail myself of such varia-

tions and modifications as come within the scope of the appended claims.

Having described my invention, what I claim as new and desire to secure by Letters Patent, is:-

70 1. A golf game comprising a representation of golf links having holes of different lengths, each hole including a tee, fairway, and green; a plurality of arbitrarily established differently spread groups of positions 75 delineated upon the fairway and extending from the tee to the green of each hole, said groups of positions being spaced apart substantially the same distance upon the various holes, each group being made up of dots 80 adapted to be distinguished from each other, said dots representing the stops for the playing strokes, and an indicator having indicia thereon relating to the positions adapted to be played.

85 2. A golf game comprising a representation of golf links having holes of different lengths, each hole including a tee, fairway, and green; a plurality of differently spread groups of arbitrary positions delineated upon the fairway of each hole, the positions in some of said rows being spaced apart 90 similar distances upon various holes, each group being made up of dots having distinguishing characteristics, said dots representing stops for the playing strokes; and a indicator having indicia thereon, the maximum indication of which bears a relation to the number of positions in some of said groups upon the various holes so that it 95 requires at least two operations of the indicator to reach the green upon the shorter holes, and at least three operations to reach the green upon the longer holes, while it requires one less operation to reach the green 100 upon the positions extending upon the green, each of such operations representing a stroke.

105 3. A golf game comprising a representation of golf links having holes of different lengths, each hole including a tee, fairway, and green; at least six arbitrarily established differently spread groups of positions delineated upon the fairway from the tee to the green of the longer holes, and at 110 least three arbitrarily established differently spread groups of positions delineated upon the fairway from the tee to the green of the shorter holes; each group being made up of dots distinguishable from each other, some dots of some groups representing hazards; and an indicator in the form of a die having one, two and three dots on three of its sides, and similar dots on the remaining three of its sides, operations of said indicator determining the advance over said positions, each operation of said indicator 115 representing a stroke.

120 4. A golf game comprising a representation of golf links having holes of different 125

lengths, each hole thereof including a tee, fairway and green; a plurality of arbitrarily established differently spread groups of positions delineated upon the fairway of each hole, there being at least three groups of positions upon the shorter holes of said course, and at least six groups of positions upon the longer holes of said course.

In testimony whereof I have signed my name to this specification in the presence of two subscribing witnesses.

LAWRENCE T. JOHNSON.
